SIPHONAGE PREVENTER FOR PLUMBING SYSTEMS

Robert R. Fox, Los Angeles, Calif.

Application September 22, 1937, Serial No. 165,140

10 Claims. (Cl. 137—69)

This invention relates generally to devices for preventing back-siphonage of water into water supply lines. The invention is applicable to water supply line outlets generally, though a particular application consists in its installation in connection with flush valves, and the invention will accordingly be herein described with that particular situation chiefly in view, but without necessary limitation thereto.

10 It is a well known fact that under certain conditions, water may be sucked backwardly through a water outlet into the water supply lines. This may be due to exhaustion of water in the mains, or to reduction of pressure in the main or in the line that supplies the outlet. Assuming the outlet to be connected to a flush valve installed in connection with a toilet bowl, the flush valve normally being held closed by the pressure in the water line, it will be seen that reduction of pressure in the mains may cause an actual suction in the water supply line, and this may cause the flush valve to open, allowing the suction to continue on down into the bowl, and in some instances may lift the water out of the bowl into the water supply line. It will further be evident that a similar occurrence is possible in various situations not involving flush valves; for instance, it is possible for back siphonage to occur in any situation in which the water outlet 20 has access to the water which it has discharged.

It is the primary object of the present invention to provide an improved device for positively preventing such back-siphonage of water into the supply line. A further object of the invention is to provide a siphonage preventer which is not only simple, but rugged and dependable in service, and one which is not liable to become disordered by reason of corrosion.

The particular characteristics of the present invention will best be understood by now referring at once to the following detailed description of a present preferred embodiment thereof, reference for this purpose being had to the accompanying drawings, in which:

45 Fig. 1 is a side elevation of the device in accordance with the present invention;

Fig. 2 is a top plan view of the device;

Fig. 3 is a vertical medial section taken on line 3—3 of Fig. 2;

50 Fig. 4 is a vertical cross section taken at right angles to Fig. 3, as indicated by lines 4—4 of Fig. 2;

Fig. 5 is an end elevation of the device;

Fig. 6 is a view looking upwardly into the upper member of the device;

Fig. 7 is a view looking downwardly into the lower member of the device; and

Fig. 8 is a fragmentary view similar to a portion of Fig. 4, showing a modification.

As mentioned above, a siphonage preventing device of the instant type may be associated with or incorporated in any conduit wherein liquid normally flows in one direction but wherein reversal of flow due to a vacuum developed ahead of the device would be objectionable. A device 10 of this type is, for instance, adapted to be used with a flush valve, such for example as of the valve disclosed in United States Patent No. 2,066,086 to E. C. Wilson, being installed in the flow line between the flush valve outlet and the 15 bowl served by the valve.

In the present illustrative embodiment of the invention, the siphonage preventer embodies a hollow body B formed with certain liquid and air passageways, in the present illustrative embodiment comprising an upper member 10, provided at the top with an internally screw-threaded inlet 11 adapted to be coupled to the discharge outlet of a flush valve, or water supply line, and a lower member 12 screw-threadedly connected to member 10 and provided at the bottom with an externally screw-threaded outlet 14 adapted for screw-threaded connection with the flow line leading to the bowl, or other container supplied by the liquid line.

30 Top member 10 may be described as generally bell shaped in external form. A hollow bridge-like member 16 extends transversely across the interior of the "bell", and has, concentric with inlet 11, a depending externally threaded annular 35 flange 17. A liquid passage or conduit 20 extends downwardly from inlet 11 to the upper surface of member 16, then divides into two branches extending outwardly and downwardly around the sides of member 16 to open to later 40 described passageways in lower member 12.

Member 10 has at the bottom a circular downwardly facing, recessed seat 22, and has aligned with hollow member 16, diametrically opposed overhanging extensions 23 outside said seat, through which extend passages 24 leading from the hollow interior 16b of member 16, said passages curving downwardly to open in a downward direction, under the "bell", as clearly illustrated in Fig. 3. Passages 24 communicate by way of hollow 16b with a circular opening or air port 25 in the lower wall 26 of hollow member 16,

50 and the lower surface of said wall 26, inside flange 17, and around port 25, affords a downwardly 55

facing valve seat 27 for a check valve 28, later to be described in more detail.

Passages 24 afford pathways for the admission of air downwardly through opening 25 when the 5 check valve is unseated from seat 27. The previously described passageway 20 will be seen to pass water entering by way of inlet 11 around the sides of member 16 defining air admission passageways 24 and downwardly to be received by 10 certain passageways in lower member 12.

Lower member 12 of the device has an annular or cylindrical external wall 30 adapted at its upper end to engage a gasket 31 placed on seat 22, and also provided with an annular wall portion 32, spaced concentrically within outer wall or casing 30, which is internally screw-threaded and adapted to be threadedly connected to externally threaded flange 17 of upper member 10. The upper end of member 32 engages a gasket 33 seating on a downwardly facing annular seat 34 formed around flange 17. Member 32 is connected to external wall 30 by diametrically opposed webs 35, spaced somewhat below the upper ends of members 32 and 30, so to form liquid spaces 36 25 between said members.

Merging with the lower portion of annular wall 32, between webs 35, is a pair of wall members 40 that extend downwardly between webs 35, each of said wall members 40 integrally joining at its ends 30 with the adjacent ends of webs 35, as indicated at 40a, so as to form, with webs 35, barriers below annular wall 32 between the spaces outside and inside said wall 32. The lower portions of these wall members 40 turn inwardly and merge with 35 a substantially horizontal wall 41 having an upwardly projecting annular flange 42 defining a liquid discharge port 43 concentric with casing 30. Formed on the upper end of flange 42 is an upwardly facing annular valve seat 44 for the previously mentioned valve 28.

A pair of vertical, horizontally spaced walls 46 join wall 41 at the top and walls 40 and webs 35 at the ends, while spaced below wall 41 and integrally joining and extending between walls 46 is 45 a horizontal wall 47 that extends between and is integrally formed with opposite sides of external casing 30.

The described wall formations provide liquid 50 passages 50 extending downwardly between walls 30 and 32, 40, leading to a liquid space 51 defined at the bottom by wall member 47. It will be observed that liquid spaces 36 between the upper portions of wall 30 and annular member 32, defined at the bottom by webs 35, communicate at 55 the ends of said webs with liquid passageways 50. If when the two parts 10 and 12 of the device are screwed together, liquid passageways 20 in upper member 10 register with passageways 50 in lower member 12, liquid discharged downwardly through 60 passages 20 is received immediately by passageways 50 and flows to liquid space 51. If, however, in the assembly of the device, liquid spaces 36 should come in part or wholly into register with liquid passages 20, the liquid from passages 20 is 65 simply received by liquid spaces 36 and flows from there to passageways 50 and thence downwardly to liquid space 51, as before.

Liquid rising from space 51 through port 43 is 70 discharged to liquid spaces or passageways 60 defined by walls 40, webs 35 and wall 30 on the outside, and by walls 46 on the inside, these passageways leading around the outside of walls 46 and beneath wall 47 to reach outlet 14, by way of which it is discharged to the discharge line or 75 plumbing fitting coupled thereto.

Normally resting on valve seat 44 around liquid discharge port 43 is the aforementioned check valve 28, preferably formed of fiber, hard rubber, or composition, such as "Bakelite." The upper side of this check valve carries a flexible sealing disc 65, preferably of soft rubber or the like, which is adapted, when check valve 28 is lifted, to seat on the aforementioned downwardly facing valve seat 27 to seal against escape of water by way of passageways 24 and ports 25. As here shown, rubber washer 65 engages in an annular groove 66 formed in check valve 28 as clearly indicated in the drawings. Valve 28 has an upwardly extending stem 68 somewhat loosely received and guided by a valve stem guide bore 69 formed within a cylindrical valve stem guide portion formed integrally with the upper wall 16a of hollow member 16.

The operation of the device is as follows. Assuming, for illustrative purposes, that inlet 11 is 20 coupled to a usual flush valve, and that outlet 14 is coupled to the line leading to the bowl served by the flush valve, the normal at-rest condition of the device is shown in Fig. 3. It will be noted that the check valve is down, resting on valve seat 25 44, and that water is present in water collection space or chamber 51 up to the level of the lower surface of valve 28. This water trapped within chamber 51 provides a desirable water seal, filtering any air that may under any circumstances be 30 drawn through port 43 due to suction in the supply line. Assuming now that suction should be developed in the supply line, sufficient to cause the flush valve to open, with the result that the suction extends down to and within chamber 51, the 35 effect is to cause valve 28 to be pressed more tightly onto its seat 44, exterior air entering by way of passageways 24 and port 25 to maintain atmospheric pressure above the valve to assure 40 tight seating on seat 44. Thus under such circumstances check valve 28 forms a barrier in the flow line, effectively preventing suction in the line ahead of the flush valve from drawing water from the bowl.

In the event that valve 28 does not seat in an 45 air-tight manner on valve seat 44, the protection afforded by the device is not vitiated. In such an instance, while the air suction is not entirely blocked by the valve, this suction is satisfied by drawing air inwardly by way of passageways 24 50 and port 25, thus breaking the siphon action and preventing the lift of water from the bowl. In some instances it may be desired to construct the device to operate in this manner, and in such an instance the check valve and lower seat 44 are 55 simply so formed as not to seat in air-tight relation.

When the flush valve is discharging through the device, the water from the flush valve enters by way of inlet 11, flows by way of passages 20 60 and 50 to chamber 51 and acts against the lower side of valve 28, elevating the latter to the position of Fig. 4. The water so flowing from chamber 51 by way of port 43 passes around the sides of walls 46 defining chamber 51, that is, by way of 65 passages 60, to reach outlet 14, through which it flows into the discharge line below. Pressure of the water flowing upwardly from port 43 holds the upper washer 65 of the check valve tightly against upper seat 27, preventing escape of water 70 at this time by way of air ports 25 and passageways 24.

In some situations the water trap feature may not be necessary, and as a modification, Fig. 8 shows a form of the invention in which a small 75

bleeder hole 47a is made in wall 47 defining chamber 51, thus permitting the water which would otherwise accumulate within chamber 51 to drain out. In such a form of the device, the 5 operation is substantially the same as in the case first described, excepting only that a body of water does not collect in chamber 51.

The device is reliable and effective in service, positively safeguarding against back siphonage. 10 The water trap or seal, which is preferably employed, is a feature of considerable advantage, serving as a barrier between the discharge pipe below and the supply line ahead.

Reference is here made to my copending application, entitled Siphonage preventer for plumbing systems (Case A), filed August 28, 1937, Serial No. 161,450, in which are made claims generic to the device disclosed and specifically claimed in the present application.

20 I have now shown and described one specific illustrative form of the invention; it will be understood however that various changes in design, structure and arrangement may be made without departing from the spirit and scope of the invention or of the appended claims.

I claim:

1. In a device of the character described, the combination of a body formed in its top with a liquid inlet, a liquid passageway within said body 30 extending laterally outwardly and downwardly from said inlet, and then formed with a reverse bend comprising a portion extending back inwardly and then upwardly, in alinement with said inlet, and terminating in an upwardly directed discharge port adapted to discharge a solid column of water, said discharge port being located in vertical alinement with said inlet, an upwardly facing valve seat around said discharge port, a liquid outlet opening from the body, a liquid passage within the body leading from said liquid discharge port to said liquid outlet, an air inlet passageway in said body terminating in a downwardly discharging port located immediately above said liquid discharge port, a downwardly 45 facing valve seat around said air port, and a check valve mounted for movement between said valve seats to close either the liquid port or the air inlet passage, said check valve being adapted to be moved onto its upper seat by virtue of flow 50 of water upwardly from said liquid port with flushing discharge through the device.

2. In a device of the character described, the combination of a body formed in its top with a liquid inlet and in its lower portion with a liquid outlet, a liquid passageway within said body extending laterally outwardly and downwardly from said inlet, and then formed with a reverse bend comprising a portion extending back inwardly and then upwardly, in alinement with said inlet, and terminating in an upwardly directed discharge port adapted to discharge a solid column of water, said discharge port being located in vertical alinement with said inlet, an upwardly facing valve seat around said discharge port, a liquid passage within the body leading from said liquid discharge port to said liquid outlet, an air inlet passageway in said body terminating in a downwardly discharging port located immediately above said liquid discharge port, a downwardly 70 facing valve seat around said air port, and a check valve mounted for movement between said valve seats to close either the liquid port or the air inlet passage, said check valve being adapted to be moved onto its upper seat by virtue of flow

of water upwardly from said liquid port with flushing discharge through the device.

3. In a device of the character described, the combination of a body formed in its top with a liquid inlet, a liquid passage within said body 5 communicating with said liquid inlet, said passage dividing below said inlet into two branches which extend outwardly in opposite directions, then downwardly, then back toward one another and join at a point below said liquid inlet, an upwardly discharging liquid port located within the body below said inlet, said port leading from the lower juncture of said liquid passage branches, a liquid passage within the body leading from the discharge side of said liquid port around said lower juncture and then downwardly to said liquid outlet, an air passage in the body leading inwardly from the exterior of the body between said branches and terminating in a downwardly discharging port located above and in communication with said liquid discharge port, and a check valve mounted for movement between said liquid and air ports, so as to close either the liquid port or the air inlet port, said check valve being adapted to be moved onto its upper seat by virtue of flow of water upwardly from said liquid port with flushing discharge through the device.

4. In a device of the character described, the combination of a body formed in its top with a liquid inlet, a liquid passage within said body 30 communicating with said liquid inlet, said passage dividing below said inlet into two branches which extend outwardly in opposite directions, then downwardly, then back toward one another and join at a point below said liquid inlet, an upwardly discharging liquid port located within the body below said inlet, said port leading from the lower juncture of said liquid passage branches, a liquid passage within the body leading from the discharge side of said liquid port and comprising 35 two branches leading around said lower juncture and then downwardly to said liquid outlet, an air passage in the body leading inwardly from the exterior of the body between said first mentioned branches and terminating in a downwardly 40 discharging port located above and in communication with said liquid discharge port, and a check valve mounted for movement between said liquid and air ports, so as to close either the liquid port or the air inlet port, said check valve being 45 adapted to be moved onto its upper set by virtue of flow of water upwardly from said liquid port with flushing discharge through the device.

5. In a device of the character described, the combination of detachably connected upper and lower casing members forming a closed body, a centrally located liquid inlet in the top of the upper casing member, a liquid outlet in the lower portion of the lower casing member, an air admission passageway opening externally of the 60 upper casing member and leading to a downwardly directed air port located below said inlet, a downwardly facing valve seat on the bottom of said member around said air port, a liquid passage within the upper member leading laterally 65 and downwardly from said inlet and discharging downwardly at a point laterally offset from the vertical axis defined by said centrally located liquid inlet, a liquid passage in the lower casing member opening upwardly in a position to receive liquid from the liquid passage in the upper member when the upper and lower casing members are connected, said last mentioned liquid passage extending downwardly, centrally and upwardly to terminate in an upwardly directed 70 75

liquid discharge port located below said air port and in alinement with said liquid inlet, an upwardly facing valve seat on the lower member around said liquid port and opposed to the valve seat around the air port, a liquid passage within the lower casing member leading from the discharge side of said liquid port to said liquid outlet, and a check valve member movable between said liquid and air port seats to close either the liquid port or the air inlet passage, said check valve being adapted to be moved onto its upper seat by virtue of flow of water upwardly from said liquid port with flushing discharge through the device.

6. In a device of the character described, the combination of screwthreadedly connected upper and lower casing members forming a closed body, a centrally located liquid inlet in the top of the upper casing member, a liquid outlet in the lower portion of the lower casing member, an air admission passageway opening externally of the upper casing member and leading to a downwardly directed air port located below said inlet, a downwardly facing valve seat on the bottom of said member around said air port, a liquid passage within the upper member leading laterally and downwardly from said inlet and discharging downwardly at a point laterally offset from the vertical axis defined by said centrally located liquid inlet, a liquid passage in the lower casing member opening upwardly in a position to receive liquid from the liquid passage in the upper member when the upper and lower casing members are connected, said last mentioned liquid passage extending downwardly, centrally and upwardly to terminate in an upwardly directed liquid discharge port located below said air port and in alinement with said liquid inlet, an upwardly facing valve seat on the lower member around said liquid port and opposed to the valve seat around the air port, a liquid passage within the lower casing member leading from the discharge side of said liquid port to said liquid outlet, and a check valve member movable between said liquid and air port seats to close either the liquid port or the air inlet passage, said check valve being adapted to be moved onto its upper seat by virtue of flow of water upwardly from said liquid port with flushing discharge through the device.

7. In a device of the character described, the combination of screwthreadedly connected upper and lower casing members forming a body, a liquid inlet in the top of the upper casing member, a liquid outlet in the lower portion of the lower casing member, walls within and formed integrally with the upper casing member defining an air admission passageway extending inwardly into the upper casing member and leading to a downwardly opening air port located below and in alinement with said liquid inlet, there being a passage for liquid flow from said inlet leading around said air passageway walls and opening downwardly outside said air port, walls within and formed integrally with the lower casing member defining a liquid passageway in said lower casing member opening upwardly in a position to receive liquid from the passageway in the upper casing member, said liquid passageway in the lower casing member extending downwardly, then centrally of the lower casing member, and finally terminating in an upwardly opening liquid port located below and in opposition to said air port, there being a passageway for liquid flow within the lower casing member from the discharge side of said liquid port downwardly past said liquid passageway defining walls to said liquid outlet, and a check valve member movable between said liquid port and air port to close either the liquid port or the air inlet passage, said check valve being adapted to be moved onto its upper seat by virtue of flow of water upwardly from said liquid port with flushing discharge through the device.

8. In a device of the character described, the combination of screwthreadedly connected upper and lower casing members forming a body, a liquid inlet in the top of the upper casing member, a liquid outlet in the lower portion of the lower casing member, walls within and formed integrally with the upper casing member defining an air admission passageway extending inwardly into the upper casing member and leading to a downwardly opening air port located below and in alinement with said liquid inlet, there being a passage for liquid flow from said inlet leading around said air passageway walls and opening downwardly outside said liquid port, walls within and formed integrally with the lower casing member defining a liquid passageway in said lower casing member opening upwardly in a position to receive liquid from the passageway in the upper casing member, engageable gasketed seats on the upper and lower casing members defining the lower opening of the liquid passage in the upper casing member and the upper opening of the cooperating liquid passage in the lower casing member, said liquid passageway in the lower casing member extending downwardly, then centrally of the lower casing member, and finally terminating in an upwardly opening liquid port located below and in opposition to said air port, there being a passageway for liquid flow within the lower casing member from the discharge side of said liquid port downwardly past said liquid passageway defining walls to said liquid outlet, and a check valve member movable between said liquid port and air port to close either the liquid port or the air inlet passage, said check valve being adapted to be moved onto its upper seat by virtue of flow of water upwardly from said liquid port with flushing discharge through the device.

9. In a device of the character described, the combination of a body formed in its top with a liquid inlet and in its lower portion with a liquid outlet, an upwardly discharging liquid port within said body vertically alined with said liquid inlet, said port being adapted to discharge a solid column of water, a chamber within the body receiving liquid from said discharge port, said chamber being in communication with said liquid outlet, an air admission passageway in said body terminating in a downwardly directed air port opening to said chamber immediately above said liquid discharge port, a check valve mounted for movement between said liquid and air ports, so as to close either the liquid port or the air inlet port, said check valve being adapted to be moved onto its upper seat by virtue of discharge of a solid column of water upwardly from said liquid port, and a liquid passage within the body leading horizontally from said liquid inlet to a point beyond the outer limits of said air and liquid ports and thence downwardly to the side of said ports, finally leading inwardly and upwardly to said liquid discharge port.

10. In a device of the character described, the combination of a body formed in its top with a liquid inlet and in its lower portion with a liquid outlet, a liquid passage within said body communicating with said liquid inlet, said passage dividing

said liquid passageway defining walls to said liquid outlet, and a check valve member movable between said liquid port and air port to close either the liquid port or the air inlet passage, said check valve being adapted to be moved onto its upper seat by virtue of flow of water upwardly from said liquid port with flushing discharge through the device.

11. In a device of the character described, the combination of screwthreadedly connected upper and lower casing members forming a body, a liquid inlet in the top of the upper casing member, a liquid outlet in the lower portion of the lower casing member, walls within and formed integrally with the upper casing member defining an air admission passageway extending inwardly into the upper casing member and leading to a downwardly opening air port located below and in alinement with said liquid inlet, there being a passage for liquid flow from said inlet leading around said air passageway walls and opening downwardly outside said liquid port, walls within and formed integrally with the lower casing member defining a liquid passageway in said lower casing member opening upwardly in a position to receive liquid from the passageway in the upper casing member, engageable gasketed seats on the upper and lower casing members defining the lower opening of the liquid passage in the upper casing member and the upper opening of the cooperating liquid passage in the lower casing member, said liquid passageway in the lower casing member extending downwardly, then centrally of the lower casing member, and finally terminating in an upwardly opening liquid port located below and in opposition to said air port, there being a passageway for liquid flow within the lower casing member from the discharge side of said liquid port downwardly past said liquid passageway defining walls to said liquid outlet, and a check valve member movable between said liquid port and air port to close either the liquid port or the air inlet passage, said check valve being adapted to be moved onto its upper seat by virtue of flow of water upwardly from said liquid port with flushing discharge through the device.

12. In a device of the character described, the combination of a body formed in its top with a liquid inlet and in its lower portion with a liquid outlet, an upwardly discharging liquid port within said body vertically alined with said liquid inlet, said port being adapted to discharge a solid column of water, a chamber within the body receiving liquid from said discharge port, said chamber being in communication with said liquid outlet, an air admission passageway in said body terminating in a downwardly directed air port opening to said chamber immediately above said liquid discharge port, a check valve mounted for movement between said liquid and air ports, so as to close either the liquid port or the air inlet port, said check valve being adapted to be moved onto its upper seat by virtue of discharge of a solid column of water upwardly from said liquid port, and a liquid passage within the body leading horizontally from said liquid inlet to a point beyond the outer limits of said air and liquid ports and thence downwardly to the side of said ports, finally leading inwardly and upwardly to said liquid discharge port.

13. In a device of the character described, the combination of a body formed in its top with a liquid inlet and in its lower portion with a liquid outlet, a liquid passage within said body communicating with said liquid inlet, said passage dividing

below said inlet into two branches which extend outwardly, then downwardly, then back toward one another and join at a point below said liquid inlet, an upwardly discharging liquid port located within the body below said inlet, said port leading from the lower juncture of said liquid passage branches, a liquid passage within the body leading from the discharge side of said liquid port around said lower juncture and then downwardly to said liquid outlet, an air passage in the body leading inwardly from the exterior of the

body between said branches and terminating in a downwardly discharging port located above and in communication with said liquid discharge port, and a check valve mounted for movement between said liquid and air ports, so as to close either the liquid port or the air inlet port, said check valve being adapted to be moved onto its upper seat by virtue of flow of water upwardly from said liquid port with flushing discharge through the device. 5

ROBERT R. FOX. 16
